(57) **CLAIM**

The ornamental design for a container simulating a basketball half-court, as shown and described.

DESCRIPTION

FIG. 1 is a top perspective view of the new design for a container simulating a basketball half-court;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

In the drawings, the broken lines showing portions of a container simulating a basketball half-court form no part of the claim.
